UNITED STATES PATENT OFFICE.

EMIL TYDEN, OF HASTINGS, MICHIGAN.

DESIGN FOR A SEAL.

SPECIFICATION forming part of Design No. 29,413, dated September 27, 1898.

Application filed August 10, 1898. Serial No. 688,306. Term of patent 14 years.

To all whom it may concern:

Be it known that I, EMIL TYDEN, a citizen of the United States, residing at Hastings, county of Barry, State of Michigan, have invented and produced a certain new and original Design for a Self-Locking Seal, which is fully set forth in the following specification, reference being had to the accompanying drawings, forming a part thereof.

10 This design relates to a self-locking seal of the variety commonly known as the "strap-seal." Such a seal is illustrated in the drawings, of which—

Figure 1 is a side elevation, and Fig. 2 an edge elevation, of the entire seal, which comprises a body A, and a strap B extending out from the body.

The characteristic or essential features of my design are contained wholly in the body A, which is bulbous or quasispherical and has a narrow thin peripheral bead or distinctly-marked rib A' and oppositely-extend-

ing wings A³ A³ approximately in the plane of said rib, presenting the appearance of a thin parallelopipedon projected through the 25 bulbous body and showing both ends protruding at opposite sides.

The essential features of my design are the bulbous or quasispherical body having the peripheral bead or distinctly-marked rib and 30 the oppositely-extending wings, which present the appearance of a thin parallelopipedon projected through the body and protruding at opposite sides thereof.

I claim—

15 The design for a seal herein shown and described.

In testimony whereof I have hereunto set my hand, in the presence of two witnesses, this 5th day of August, 1898.

EMIL TYDEN.

Witnesses:

W. D. HAYES,
J. T. LOMBARD.
